Primary Examiner—Susan J. Lucas*Assistant Examiner*—Pamela Burgess*Attorney, Agent, or Firm*—Loeb & Loeb LLP**[57] CLAIM**

The ornamental design for an educational board and pieces therefor, shown and described.

DESCRIPTION

FIG. 1 is a top perspective view of an educational game board and pieces therefor, showing our new design with the pieces positioned on the board;

FIG. 2 is a top perspective view of the pieces used in conjunction with the board, the board being omitted for convenience of illustration; and,

FIG. 3 is an enlarged exploded perspective view of a portion of the top of the board and the bottom of the pieces therefor.
